UNITED STATES PATENT OFFICE

ORVILLE S. CAESAR, OF CLEVELAND, OHIO, ASSIGNOR TO TROPIC-AIRE, INCORPORATED, OF MINNEAPOLIS, MINNESOTA, A CORPORATION OF DELAWARE

VEHICLE STORM SASH

Application filed March 5, 1927, Serial No. 173,176. Renewed August 1, 1930.

This invention relates to new and useful improvements in storm sashes, and more particularly relates to an improved storm sash adapted for use on closed vehicles, such as sedans and busses, and an object of the invention is to provide such a device which may readily be installed in the usual sash frame of a vehicle body and which storm sash is relatively lower in height than the opening in said sash frame, whereby an air-circulating passage will be provided between the top of the storm sash and the upper portion of the sash frame, when the vehicle sash is lowered to an open position. A further object of the invention is to provide a storm sash having means for demountably securing it to a vehicle sash frame in spaced relation to the usual sash thereof and said storm sash having a flexible web secured to the upper inner portion thereof, adapted to engage the adjacent surface of the vehicle sash, thereby to provide substantially an air-tight chamber between the storm sash and the vehicle sash. A further object of the invention is to provide a storm sash having a flexible member, preferably of T-shaped cross section, and demountably secured to the upper inner portion thereof and laterally extending therefrom with its inner edge positioned to be engaged by the vehicle sash, thereby to provide substantially an air-tight chamber between said sashes when the vehicle sash is in closed position. A particular object of the invention therefore, is to provide an improved storm sash adapted for use on automotive vehicles of the closed type, and other objects of the invention will appear from the following description and accompanying drawings and will be pointed out in the annexed claims.

In the accompanying drawings there has been disclosed a structure designed to carry out the various objects of the invention, but it is to be understood that the invention is not confined to the exact features shown as various changes may be made within the scope of the claims which follow.

In the accompanying drawings forming part of this specification;

Figure 1 is a perspective view showing a portion of an automobile body with the invention applied thereto;

Figure 2 is an enlarged vertical sectional view showing the relative position of the storm sash with respect to the vehicle sash and also showing the means at the upper portion thereof for closing the gap between the two sashes;

Figure 3 is a side elevation of Figure 2;

Figure 4 is a view similar to Figure 2, showing the vehicle sash in open position;

Figure 5 is an enlarged detailed sectional view on the line 5-5 of Figure 4, showing the manner of mounting the storm sash in the vehicle sash frame;

Figure 6 is a perspective view showing the upper inner portion of the storm sash; and

Figure 7 is a perspective view of the flexible member adapted to close the gap between the two sashes to provide an air-tight chamber therebetween.

In the selected embodiment of the invention here shown, for purposes of disclosure, there is illustrated a portion of an automotive vehicle body, comprising the usual sash frames 11 in which the usual sashes 12 are slidably mounted in suitable run-ways 13, as shown in Figures 2 and 4.

The novel sash featured in this invention comprises a rectangular frame, constructed of sheet metal as shown in Figure 5. The frame comprises an outer plate 14 and an inner plate 15 having their inwardly turned edges spaced apart to receive filler blocks 16 and the flexible sash retainers 17 as shown, which are grooved to receive the storm sash 18 so that an air-tight joint is provided between the sash and its supporting frame. The upright portions of the storm sash frame are offset as shown at 19 and the outwardly turned portions 20 and 21 of the plates 14 and 15, respectively, are adapted to be seated against the uprights 11 of the storm sash frame. Suitable gaskets or packings 22 are interposed between the flanges 21 and the uprights 11 of the sash frame to provide air-tight joints therebetween. The storm sash

70

100

frame may be secured to the uprights 11 by such means as screws 23.

The plates 14 and 15, comprising the lower rail of the storm sash frame, are turned outwardly and downwardly inclined to provide an inclined flange 24 adapted to be seated against the sill 25 of the sash frame. A suitable packing 26 is similarly interposed between the flange 24 and the sill 25.

10 At the upper portion of the storm sash frame, the upper edges 27 and 28 of the plates 14 and 15 are bent over the top of the sash frame and seated, one upon the other, and suitably secured together to provide a rigid frame structure. A filler 16 is also interposed in the upper portion of the sash frame against which the storm sash retainer 17 is seated as shown.

15 A feature of this invention resides in the particular arrangement of the storm sash 18 with respect to the vehicle sash 12. Referring to Figures 2, 3, and 4, it will be noted that the over all height of the storm sash is relatively lower than the height of opening 25 of the vehicle sash frame so that an air-circulating passage 34 is provided between the upper edge of the storm sash and the head jamb or rail 35 of the vehicle sash frame. Thus, when the vehicle sash 12 is opened to 30 the position shown in Figure 4, air may circulate through the air-circulating passage provided above the storm sash, as indicated by the arrows in Figure 4. It will also be noted that the storm sash is spaced from the vehicle sash so as to provide a dead air space therebetween.

35 To thus provide a dead air space between the two sashes, means are provided for closing the gap between the two sashes at the upper portion of the storm sash. Such means consists of a flexible member or web 29 having a T-head 30 demountably received in a holder 31 secured to the upper, inner portion of the storm sash frame as shown 40 in Figures 2 and 4. The web 29 is tapered inwardly as shown in Figures 4 and 7 so that substantially a knife edge 32 is provided, which is adapted to engage the inner surface of the vehicle sash 12, when the latter is 45 moved upwardly to closed position as shown in Figure 2. The web 29 is of such width that it must flex as shown in Figure 2, when engaged by the vehicle sash 12, thus closing the gap between the two sashes and providing 50 substantially an air-tight chamber therebetween, with the resultant elimination of the accumulation of frost upon the inner sash 12. The web 29 also extends the full length of the storm sash or substantially the width of the 55 vehicle sash opening.

60 A suitable rain shield 33 is secured to the upper portion of the sash frame to prevent rain and moisture from entering through the air-circulating passage 34, when the inner

sash 12 is in open position as shown in Figure 4.

The construction of the novel storm sash featured in this invention is comparatively simple and inexpensive and its frame is so constructed that it may readily and quickly be mounted in a vehicle sash opening as shown in the drawings. The flexible member or web 29 closes the gap between the two sashes so as to provide a dead air space therebetween, when the upper edge of the vehicle sash 12 is raised to a position above the storm sash 18, or, when in closed position as shown in Figure 2. By providing the flexible web 29 with a T-head as shown in Figure 7, it 75 may readily be removed from the holder 31 for repairs or replacement when necessary. The general construction of the storm sash frame is also such that when mounted in a sash opening and secured thereto, the joints 80 between the storm sash frame and the uprights 11 and sill 25 of the sash frame will be substantially air tight. This is an important feature in structures of this type as it 85 positively prevents frosting of the windows or sash in cold weather.

I claim as my invention:

1. In combination, a vehicle sash frame having a glazed panel slidable therein, a storm sash, including a frame having oppositely extending flanges adapted to be seated against the outer surfaces of the vehicle sash frame, said flanges being offset from the medial plane of the storm sash whereby said sash will be positioned within the opening of the vehicle sash frame, a channel member secured to the upper inner portion of the storm sash frame, and flexible means demountably supported in said channel member and adapted to engage the surface of said panel to provide substantially an air-tight joint between the storm sash and said glazed panel.

2. In combination, a vehicle sash frame having a glazed panel slidable therein, a storm sash mounted in the opening in said vehicle sash frame and having its top edge spaced from the upper portion of said frame to provide an air circulation passage, said storm sash comprising a frame having its opposite sides provided with offset flanges adapted to be fitted against the outer surfaces of said vehicle sash frame, whereby the storm sash will be positioned within the opening in the vehicle sash frame, a channel secured to the upper inner portion of the storm sash frame, and a flexible tongue demountably received in said channel and having its inner edge arranged to engage the surface of said glazed panel to provide substantially an air-tight joint between the upper portion of the storm sash and said glazed panel.

3. In combination, a vehicle sash frame having a glazed panel slidable therein, a

storm sash mounted in the opening in said vehicle sash frame and having its upper edge spaced from the upper portion of said frame to provide an air circulation passage, the 5 side frame members of said storm sash being of angle iron cross-section to provide oppositely extending flanges offset from the medial plane of said sash, whereby the storm sash will be positioned in the opening in said vehicle sash frame, when said flanges are seated against the outer surfaces of the sash frame, a channel member secured to the upper inner portion of the storm sash frame, a 10 flexible member having a T-shaped head adapted to be demountably received in said channel member and having a tongue positioned to engage the adjacent surface of said glazed panel, to provide substantially an air-tight joint between the upper portion of the 15 storm sash and said panel, and permitting freedom of movement of the vehicle sash, and a rain shield secured to the upper portion of the vehicle sash frame and overhanging the upper edge of the storm sash to prevent rain and snow from entering the vehicle, when the glazed panel is lowered to an 20 open position.

4. In combination, a vehicle sash frame having a glazed panel movable therein, a 25 storm sash, including a frame having oppositely extending flanges adapted to be seated against a surface of the vehicle sash frame, a channel member secured to the upper inner portion of the storm sash frame, and flexible means demountably supported in said channel member and adapted to engage the surface of said glazed panel to provide substantially an air-tight joint between the storm sash and said glazed panel.

50 In witness whereof, I have hereunto set my hand this 2nd day of March, 1927.

ORVILLE S. CAESAR.
